PILE FABRIC LOOM

Samuel P. Parker, La Grange, Ga., assignor to
Callaway Mills Company, La Grange, Ga., a
corporation of Georgia

Application March 23, 1950, Serial No. 151,370

8 Claims. (Cl. 139—38)

1

This invention relates to pile fabric looms provided with means for periodically engaging and drawing out pile yarns from the shed to form loops, which are bound in place, as the weaving continues, to form a pile. Such looms are ordinarily employed in the weaving of fabrics having a pile of loops of such length, that they cannot be made on pile fabric looms having wires over which the pile yarns are raised to form pile loops. More particularly, the invention is concerned with a novel loom operating in the manner described, which is superior to prior similar looms, in that the shedding and shuttle motions operate continuously instead of stopping during the drawing out of the pile loops, as in prior looms.

The loom of the invention includes separate means for supplying pile and ground warp yarns and means for forming the pile and ground warp yarns into sheds, the shedding means operating to raise the pile warp yarns higher than the ground warp yarns in the upper line of the shed. The loom also includes the usual shuttle motion and a lay carrying a reed, by which the inserted weft threads are beaten up. The reed is mounted on the lay for endwise movement and means are provided for shifting the reed and thereby moving the warp threads laterally periodically during the weaving operation. The pile warp yarns are drawn out to form loops by hooks carried by a bar mounted for oscillatory movement, preferably on arms freely mounted on the shaft, on which the lay swords are mounted. The loom includes means for periodically moving the bar back to cause the hooks to pass between the raised pile warp yarns and then moving the bar forward. When the hooks have passed between the pile warp yarns, the reed is shifted laterally to cause the yarns to be caught by the hooks, so that, in the forward movement of the bar, the hooks draw out the yarns. Preferably, the movements of the bar are effected by connecting the arms supporting the bar to the lay to move back therewith and by so constructing the lay and arms, that the lay pushes the arms and bar forward. The hooks are of a novel construction such that the loops automatically detach themselves from the hooks, as the weaving proceeds. Also, means are provided for rocking the bar on its axis to vary the length of the loops drawn out.

For a better understanding of the invention, reference may be made to the accompanying drawings, in which

Fig. 1 is a vertical longitudinal section through the new loom;

2

Figs. 2, 3 and 4 are sectional views on the lines 2—2, 3—3, and 4—4, respectively, of Fig. 1;

Fig. 5 is a vertical sectional view of parts of the loom, showing their different positions in operation;

Fig. 6 is a sectional view of a detail of the loom on the line 6—6 of Fig. 5;

Figs. 7 and 8 are vertical longitudinal sectional views of parts of the loom, showing their different positions in operation;

Fig. 9 is a detail of Fig. 8 on an enlarged scale;

Figs. 10 and 11 are plan views showing the manner in which the pile warp yarns are caught by the hooks; and

Fig. 12 is a view similar to Fig. 9 showing the hook bar in its forward position.

The loom illustrated in the drawings comprises the usual sides 15 connected at one end by a breast beam 16, over which the woven fabric 17 (shown as plain goods, for convenience) passes to the take-up roll 18. The ground warp yarns 19 are supplied from a beam 20 mounted in the loom sides and pass from the beam over a whip roll 21 and thence to a pair of conventional harness frames 22, 23. The pile warp yarns 24 are drawn from a supply (not shown) and pass beneath a guide roller 25, over a rubber-covered friction roller 26, and beneath a bar 27 mounted in the ends of arms 27a, the other ends of which are pivoted on the shaft 26a of roller 26. From the bar 27, the pile warp yarns pass to a harness frame 28, which is actuated to raise the pile warp yarns higher than the ground warp yarns 19a in the upper line of the shed.

The loom is provided with the usual lay 29 including swords 30 pivotally mounted on a shaft 31 extending between the loom sides. The lay is swung back and forward in the usual way by a connecting rod 32 driven by a crank on the loom crank shaft (not shown). The lay carries a reed 33 made up of a base bar 34 mounted for sliding movement in a channel in the top of the lay, a top bar 35 mounted for sliding movement in the reed cap 36 attached to the lay, and the usual dents 37 extending between the bars 34, 35. The base bar 34 carries a pin 38 projecting to the rear through an opening in the wall of the channel, in which bar 34 is mounted, and the pin lies in a slot in the end of one arm of a bell crank 39 pivoted on the lay. The other arm of the crank is connected to a rod 40, which is connected through a bell crank 41 and a rod 42 to a lever 43 carrying a roller 44 engaging a cam 45 on the loom pick shaft 46. As the shaft rotates, the cam acts through the connections described to shift the reed to the right on the lay,

55

as viewed from the front. This movement of the reed is opposed by a spring 47, which is connected at one end to one of the bars 48 supporting the reed cap 36 on the lay and, at the other end, to a bar 49 extending between the top and base bars of the reed. The spring restores the reed to its normal position, after it has been shifted by cam 45.

A pair of arms 50 are mounted for swinging movement on shaft 31 and a bar 51 extends between the arms and is provided at each end with a circular gear segment 52 having a central pivot pin 53 received in an opening in the adjacent arm 50. Each segment 52 meshes with a gear 54 held fast by a set screw on a pin 55 rigidly attached to a lever 56 near the upper end thereof, and loosely received in an opening in the arm 50. Each lever has a slot 57 near its lower end, through which extends a stud 58 adjustably mounted in a fixed part 59 of the loom.

A double-ended hook 60 is pivotally mounted on each arm 50 near the upper end thereof and the hook is connected by a rod 61 to one arm of a bell crank 62 pivoted on arm 50. The other arm of the bell crank 62 is connected by a rod 63 and a second bell crank 64 to a rod 65, which is operated at suitable intervals during the weaving cycle by a control device (not shown), such as a dobby mechanism, jacquard, etc. In the position of arms 50 shown, the arms are in the forward position against rubber blocks 66 on the rear face of the breast beam 16 and the forward end of hook 60 is engaged with a catch 67 on the breast beam. The lay is provided with a catch 68 engageable by the back end of hook 60 and the lay also carries rubber blocks 69 engageable with arms 50.

The bar 51 has attached to it a plurality of pile hooks 70 extending rearwardly warpwise beyond the rear side of the bar. Each pile hook 70 is made of a strip of metal and has a straight side 71, which lies parallel to the warp yarns. The other side 72 of the strip is inclined toward the straight side in a rearward direction. Near the free end of the strip, the inclined side 72 is formed with a projection or bill 73 and the outer side 74 of the bill is inclined at about 45° to the straight side 71 of the strip and, with the straight side, forms the point 75 of the hook. The bar 51 carries as many pile hooks 70 as there are pile yarns 24 in the fabric.

In the operation of the loom, the pile and ground warp yarns are formed into successive sheds in the usual way and a pick of filling is laid in each shed by the shuttle and is then beaten up by the lay. During these operations, the arms 50 and bar 51 are held against the breast beam by engagement of the forward ends of hooks 60 with catch 67 on the breast beam. When a row of pile loops is to be formed, the pile yarns 24 are in the upper line of the shed and higher than the upper ground warp yarns. When the pick has been inserted in that shed, hooks 60 are swung by upward movement of rods 65 by the control mechanism so that the forward ends of the hooks 60 are disengaged from catches 67 and the back ends of the hooks engage the catches 68 on the lay to connect arms 50 to the lay. As the lay moves to the rear, arms 50 and bar 51 move with it and the pile hooks 70 on the bar pass between the raised pile warp yarns, when the lay is in its extreme rear position. When the pile hooks are between the pile warp yarns, the reed is shifted on the lay by the action of cam 45 on lever 43 and the connections between the lever and bell crank 38 engaging pin 38 on the reed. This shift-

ing of the reed causes the pile warp yarns to be shifted to a position behind the projections 73 on the pile hooks, as shown in Fig. 11. As the lay moves forward, blocks 69 on the lay engage arms 50 and move the arms and hook bar 51 forward. This movement of bar 51 causes the pile hooks 70 to draw out loops 19b of the pile yarns and, when arms 50 are against the blocks 66 on the breast beam, hooks 60 are actuated by rods 65 and engage catch 67 to hold the bar 51 and arms 50 in the forward position, while the weaving proceeds until another row of pile loops is to be formed.

The function of levers 56 is to determine the downward limit of the travel of hooks 71 as they pass between the raised pile yarns 24, and the levers operate as follows. When arms 50 swing to the rear with the lay, the levers 56 are swung to the rear with the arms and, since the studs 58, on which the levers swing, lie in a vertical plane forward from the vertical plane through shaft 31, on which the arms swing, the gears 54 fast on pins 55 attached to levers 56 are moved angularly relative to gear segments 52 in such direction that the free ends of hooks 71 move angularly upwardly. Accordingly, as the hook bar 51 is carried to the rear with arms 50 along an arcuate path having the axis of shaft 31 as the center, the bar is also being rocked on the axis of pins 53 in such direction that the free ends of the hooks are swung upwardly away from the yarns as indicated by the upper dotted lines at the left in Fig. 5. When the hook bar moves forward, it is rocked in such direction that the free ends of the hooks are swung downwardly.

If it is desired to shorten the length of the loops, the set screws holding gears 54 fast on pins 55 are loosened, the gears are turned in such direction as to move the gear segments 52 to swing hook bar 51 to lower the free ends of the hooks, and the set screws are tightened. If nothing more were done, the hooks 71 on their movement between the raised pile yarns 24 would move downward so far that they might pass between and engage the raised warp yarns 19a. Accordingly, whenever the hook bar is adjusted as described to make shorter loops, the studs 58, on which levers 56 are pivoted, are raised a corresponding distance in their slots 57 to shorten the effective length of levers 56. By proper adjustment of studs 58, the angular movement of the hook bar 51, which tends to raise the free ends of the hooks and occurs when the hook bar is carried to the rear with arms 50, may be so adjusted that the hooks will pass between pile yarns 24 but not between warp yarns 19a at the limit of the rearward travel of the hooks. Similarly, if longer loops are desired, the gears 54 are turned in such direction as to raise the free ends of the hooks and are then held fast. At the same time, the effective length of levers 56 is increased by lowering studs 58 in slots 57.

After the pile hooks have drawn the pile warp yarns out to make pile loops, the pile hook bar 51 remains at rest for any desired number of pairs of picks. When another row of loops is to be inserted, hooks 60 are actuated under the control of the pattern mechanism to connect arms 50 to the lay, as above described. As the pile hooks 70 move back, they automatically free themselves from the loops because of the shape of the hooks. Thus, as shown in Fig. 11, when a loop of pile yarn is held by a pile hook, the point 75 of the hook lies offset from the plane of the loop and, when the hook moves back, the inclined outer side 74 of the bill 73 of the hook, engages the

inner surface of the yarn in the loop and forces the loop aside, so that the loop is freed from the hook.

In the operation of the new loom, the weaving proceeds without interruption, in that the pile hooks move back with the lay to engage the pile warp yarns and move forward with the lay to draw the yarns out to form loops. The weaving of the ground then continues and, when another row of loops is to be formed, the pile hooks are again moved back with the lay. The new loom thus operates at a speed comparable with that of plain goods looms and is much more efficient than prior pile fabric looms having pile hooks, since, in such looms, the weaving is interrupted while the pile hooks are moved back to engage the pile warp yarns and then moved forward to draw out the yarns. In the new loom, the pile hooks are rigidly attached to the hook bar and are so constructed that the loops free themselves from the hooks. The prior looms are more complicated, in that the hooks are swung or rotated to catch the pile warp yarns and must be operated in some fashion to free themselves from the hooks.

I claim:

1. In a loom, having pattern mechanism the combination of separate means for supplying pile and ground warp yarns, means for forming the pile and ground warp yarns into sheds, said means raising the pile warp yarns higher than the ground warp yarns in the upper line in the shed, means for inserting a weft yarn in each shed, a lay carrying a reed and mounted to swing about an axis to cause the reed to beat up the inserted weft yarns, the reed being mounted on the lay for endwise movement transversely of the lay, a pair of arms mounted to swing about the same axis as the lay, a bar mounted on the arms and carrying a plurality of hooks extending warpwise, means for connecting the bar to the lay to move rearwardly therewith to pass the hooks between the pile warp yarns, the lay returning the bar to its initial position, means controlled by the pattern mechanism for rendering the connecting means effective, and means for shifting the reed endwise, when the hooks are between the pile yarns, to cause the pile warp yarns to be caught by the hooks.

2. In a loom, the combination of separate means for supplying pile and ground warp yarns, means for forming the pile and ground warp yarns into sheds, said means raising the pile warp yarns higher than the ground warp yarns in the upper line of the shed, means for inserting a weft yarn in each shed, a lay carrying a reed and mounted to swing about an axis to cause the reed to beat up the inserted weft yarns, the reed being mounted on the lay for endwise movement transversely of the lay, a pair of arms mounted to swing about the same axis as the lay, a bar mounted on the arms and carrying a plurality of hooks extending warpwise, means for intermittently moving the arms and bar back and forward with the lay, the hooks passing between the raised pile warp yarns in the back movement of the bar, and means for shifting the reed endwise, when the hooks are between the pile yarns, to cause the pile warp yarns to be caught by the hooks.

3. In a loom, the combination of separate means for supplying pile and ground warp yarns, means for forming the pile and ground warp yarns into sheds, said means raising the pile warp yarns higher than the ground warp yarns in the upper line of the shed, means for inserting a weft yarn

in each shed, a lay carrying a reed and mounted to swing about an axis to cause the reed to beat up the inserted weft yarns, the reed being mounted on the lay for endwise movement transversely of the lay, a bar mounted above the warp yarns for oscillatory movement about the same axis as the lay and for oscillatory movement about a second axis lengthwise of the bar and close to the bar, a plurality of hooks mounted on the bar and extending warpwise, means for intermittently moving the bar back and forward with the lay and rocking the bar on said second axis, the free ends of the hooks rising as the lay moves back and falling as the lay moves forward and the hooks passing between the raised pile warp yarns in the back movement of the bar, and means for shifting the reed endwise, when the hooks are between the pile warp yarns, to cause the pile warp yarns to be caught by the hooks.

4. In a loom, the combination of separate means for supplying pile and ground warp yarns, means for forming the pile and ground warp yarns into sheds, said means raising the pile warp yarns higher than the ground warp yarns in the upper line of the shed, means for inserting a weft yarn in each shed, a lay carrying a reed and mounted to swing about an axis to cause the reed to beat up the inserted weft yarns, the reed being mounted on the lay for endwise movement transversely of the lay, a pair of arms mounted to swing about the same axis as the lay, a bar pivotally mounted on the respective arms to swing about an axis parallel to and offset from the axis, about which the lay swings, the bar extending transverse to the warp yarns, a plurality of hooks mounted on the bar to extend warpwise, means for intermittently moving the arms and bar back and forward with the lay and simultaneously rocking the bar on the arms to raise the free ends of the hooks, as the bar moves to the rear, and to lower the free ends of the hooks, as the bar moves forward, the hooks passing between the raised pile warp yarns in the back movement of the bar, and means for shifting the reed endwise, when the hooks are between the pile warp yarns, to cause the pile warp yarns to be caught by the hooks.

5. In a loom, the combination of separate means for supplying pile and ground warp yarns, means for forming the pile and ground warp yarns into sheds, said means raising the pile warp yarns higher than the ground warp yarns in the upper line of the shed, means for inserting a weft yarn in each shed, a lay carrying a reed and mounted to swing about an axis to cause the reed to beat up the inserted weft yarns, the reed being mounted on the lay for endwise movement transversely of the lay, a pair of arms mounted to swing about the same axis as the lay, a bar pivotally mounted at its ends on the respective arms and extending transverse to the warp yarns, a plurality of hooks mounted on the bar to extend warpwise, means for intermittently moving the arms and bar back and forward with the lay, adjustable means for rocking the bar on the arms to raise the free ends of the hooks a selected distance during the movement of the bar to the rear and to lower the free ends of the hooks a selected distance during the movement of the bar forward, the hooks passing between the raised pile warp yarns in the back movement of the bar, and means for shifting the reed endwise, when the hooks are between the pile warp yarns, to cause the pile warp yarns to be caught by the hooks.

6. In a loom, the combination of separate means for supplying pile and ground warp yarns, means for forming the pile and ground warp yarns into sheds, said means raising the pile warp yarns higher than the ground warp yarns in the upper line of the shed, means for inserting a weft yarn in each shed, a lay carrying a reed and mounted to swing about an axis to cause the reed to beat up the inserted weft yarns, the reed being mounted on the lay for endwise movement transversely of the lay, a pair of arms mounted to swing about the same axis as the lay, a bar pivotally mounted at its ends on the respective arms and extending transverse to the warp yarns, a plurality of hooks on the bar extending warpwise, hook means operable to connect the arms to the lay to move back with the lay, the arms being pushed forward by the lay, means for operating the hook means intermittently, means for rocking the bar on the arms to raise the free ends of the hooks during the movement of the bar to the rear and to lower the free ends of the hooks during the movement of the bar forward, the hooks passing between the raised pile warp yarns in the back movement of the bar, and means for shifting the reed endwise, when the hooks are between the pile warp yarns, to cause the pile warp yarns to be caught by the hooks.

7. In a loom, the combination of separate means for supplying pile and ground warp yarns, means for forming the pile and ground warp yarns into sheds, said means raising the pile warp yarns higher than the ground warp yarns in the upper line of the shed, means for inserting a weft yarn in each shed, a lay carrying a reed and mounted to swing about an axis to cause the reed to beat up the inserted weft yarns, the reed being mounted on the lay for endwise movement transversely of the lay, a pair of arms mounted to swing about the same axis as the lay, a bar pivotally mounted on the respective arms and extending transverse to the warp yarns, a plurality of hooks on the bar extending warpwise, a pair of levers pivoted on the respective arms, connections between the levers and bar, means for intermittently moving the arms and bar back and forward with the lay, means for rocking the

levers during the movement of the arms and through the connections rocking the bar, the hooks passing between the raised pile warp yarns as the bar moves to the limit of its backward movement, and means for shifting the reed endwise, when the hooks are between the pile warp yarns, to cause the pile warp yarns to be caught by the hooks.

8. In a loom, the combination of separate means for supplying pile and ground warp yarns, means for forming the pile and ground warp yarns into sheds, said means raising the pile warp yarns higher than the ground warp yarns in the upper line of the shed, means for inserting a weft yarn in each shed, a lay carrying a reed and mounted to swing about an axis to cause the reed to beat up the inserted weft yarns, the reed being mounted on the lay for endwise movement transversely of the lay, a pair of arms mounted to swing about the same axis as the lay, a bar mounted on the arms and carrying a plurality of hooks extending warpwise, a pair of hooks pivoted on the arms, means for intermittently swinging the pivoted hooks to connect the arms to the lay to swing back therewith, the hooks on the bar passing between the raised warp yarns as the arms and bar move back, the arms and bar being pushed forward by the lay, and means for shifting the reed endwise, when the hooks are between the pile warp yarns, to cause the pile warp yarns to be caught by the hooks.
